UNITED STATES PATENT OFFICE.

WILLIAM J. VAN OSDEL, OF CHICAGO, ILLINOIS, ASSIGNOR OF ONE-HALF TO LOUIS SPERLING, OF CHICAGO, ILLINOIS.

SELF-WINDING CLOCK.

1,191,249.

Specification of Letters Patent.

Patented July 18, 1916.

Application filed June 7, 1915. Serial No. 32,484.

To all whom it may concern:

Be it known that I, WILLIAM J. VAN OSDEL, a citizen of the United States, residing at Chicago, in the county of Cook and State of Illinois, have invented certain new and useful Improvements in Self-Winding Clocks, of which the following is a specification.

This invention relates to improvements in self-winding clocks of the electric type and one of the objects of the invention is to simplify the construction of the same and provide an improved device of this character embodying gravity controlled means for actuating the same, and improved electro-responsive means for positioning the said gravity means in an operative position, the said electro-responsive means embodying an armature for shifting the gravity controlled means and having improved means for overcoming sparking between the contacts when the circuit is made and broken.

A further object is to provide improved means for maintaining a constant and steady operation of the balance wheel during the time that the gravity controlled operating means is shifted to an operative position.

To the attainment of these ends and the accomplishment of other new and useful objects, as will appear, the invention consists in the features of novelty in substantially the construction, combination and arrangement of the several parts, hereinafter more fully described and claimed and shown in the accompanying drawings illustrating the invention, and in which;

Figure 1 is a rear elevation of an apparatus of this character, constructed in accordance with the principles of this invention. Fig. 2 is a left hand end elevation of the parts shown in Fig. 1. Fig. 3 is a detail sectional view taken on line 3—3, Fig. 2. Fig. 4 is a sectional view taken on line 4—4, Fig. 3.

Referring more particularly to the drawings and in the present exemplification of this invention, the numeral 10 designates generally a frame-work of a clock movement, having the usual balance wheel 11, and 12 designates an operating shaft by means of which motion is imparted to the clock movement, a dial 13 being also provided and over which dial the hands 14 of the clock move.

Connected with the shaft 12, and preferably exterior of the supporting frame is a

collar designated generally by the reference numeral 15 (see particularly Fig. 4) and this collar is held fast to the shaft 12 by means of a set screw 16; and the collar is provided with a shoulder against which a disk 17 loosely mounted on the collar rests, and the collar is also provided with shoulders 18 and 19.

Loosely mounted upon the shoulder 18 is a ratchet wheel 20, and this ratchet wheel is held in place against displacement with respect to the collar by means of arm 21, which is in turn mounted upon the shoulder 19 and secured thereto for rotation therewith by means of a suitable fastening device 22, such as a set screw, so that when the arm 21 is rotated, the collar 15 and shaft 12 will be simultaneously rotated, and moved relatively with respect to the ratchet wheel 20.

Connected with the arm 21 is a spring 23, which extends parallel with the arm and one end 24 of the spring is normally spaced from the arm 21, as shown more clearly in Fig. 3, and is adapted to be moved into and out of position with respect to the arm 21 to place stress upon the spring 24 by means of a pin or projection 25, which is connected with and projects laterally beyond the face of the ratchet wheel 20, so that when the ratchet 20 is moved relatively with respect to the collar 15, the spring 23 will be compressed with respect to the arm 21 for a purpose to be hereinafter set forth. Motion is imparted to the ratchet wheel preferably by means of an arm 26 upon which is adjustably mounted a weight 27, and this arm is connected with the disk 17 the latter being pivotally supported as at 28.

Connected with the disk 17, preferably to an extension 17^a on the disk, is a pawl 29 which engages and coöperates with the teeth of the ratchet wheel 20 and serves as a means for rotating the ratchet wheel 20 when the arm 26 moves under the influence of the weight 27. A retaining pawl 30 also coöperates with the ratchet wheel 20 and serves the purpose of holding the ratchet wheel against retrograde movement.

Pivotally mounted upon a suitable support, and intermediate its ends is an arm 31, having a weight 32, and this arm is so arranged that the end 33 thereof projects into the path of a retrograde movement of a pin or projection 34 on the disk 17, so that when the arm 26 is raised, in a manner to be set

- forth, to an initial or starting position, the projection 34 will engage the end 33 of the arm 31 and will act as a stop for the arm 26. This weighted arm 31 also acts as a means for equalizing the weighted arm 26 so that when the latter is in a vertical position, and less power is applied to the gear train from the arm 26, the weighted arm 31 assists in initially moving the arm 26. This arm 31 also serves to prevent the arm 26 from being thrown too far. An adjustable stop 35 may also be provided for limiting the movement of the arm 31 in both directions. This stop is pivotally supported by means of a screw 35^a, and has a laterally projecting portion extending over the arm, to be engaged thereby, and the stop is held in its adjusted position about its pivot by tightening the screw 35.
- 20 The arm 26 is adapted to be moved from an inoperative to an operative position by any suitable electro-responsive device 36, which is supported in any suitable manner, and batteries 37 are provided which are connected with the coils of the electro-responsive device. The batteries 37 are preferably incased within a casing 38, the cover 39 of which is here shown as serving as a support for the clock mechanism. An armature 40 is provided which acts under the influence of the electro-responsive device, and this armature is provided with a portion 41 in the shape of an arm which inclines backwardly and projects for some distance above the electro-responsive device and terminates adjacent the ratchet wheel 20.
- 25 The arm 41 is provided with a contact stud 42, and a contact 43 cooperates with the stud 42. This contact 43 is connected with but insulated from the arm 41 by means of suitable insulation 44, and the end of the contact 43 projects beyond the end of the arm 41 and is bent thereover as at 45 so that the extremity 46 will be inclined as shown 30 and terminates adjacent the stud 42, the extremity 46 also projecting into the path of movement of the stud or projection 34 on the disk 17. With this arrangement all sparking is obviated, because when the weighted arm 26 moves the ratchet 20 and the disk 17, contact will be first made between the projection 34 on the disk and the extremity 46 of the contact 43 during the movement of the weighted arm 26 in a downward direction. This will complete the circuit through the coil 36 to attract the armature 41. Before the armature engages the core or pole piece, the contact 42 moves into engagement with the extremity 46 of the contact 43.
- 35 When the armature engages the pole piece it has a tendency to throw the disk 17 forward, assisted by the spring action of the extremity 46 of the contact 42, and this spring action also causes the extremity 46 of the contact 43 to move out of

engagement with the contact 42, while the said extremity is still in engagement with the projection 34, thereby avoiding sparking between the extremity 46 and the contact 42. A further movement of the weighted arm 26 in the same direction will cause the contact 46 to engage the stud 42 thereby making a second contact between the stud 42 on the armature and the contact 46.

When the electro-responsive device 36 is energized by the completion of the circuit, the armature 40 will be attracted and this movement of the armature will cause the arm 41 to be forced in a direction to rotate the arm 26 about the pivot 28 through the medium of the projection 34 on the disk 17 and thereby raise the weighted arm 26 to an operative position. The arm will travel under the influence of the armature for a portion of its movement and the momentum imparted to the arm 26 by the armature will cause the arm to travel a portion of its distance under the influence of its momentum, the movement of the arm being arrested by means of the weighted arm 31.

When the circuit is broken, the stud 42 and contact 46 are first separated and inasmuch as the contact 46 is still in contact with the projection 34, no sparking will take place between the contacts 46 and 42, with the result that these contacts will not become corroded, thereby always insuring operation of the parts, and the springy nature of the contact 46 with respect to the contact 42 insures a slight sliding movement of these two contacts, one with respect to the other, which maintains both of the parts bright or polished, thereby obviating the necessity of the use of platinum. This sliding action of the contacts 46, 42 is effected by reason of the springy nature of the contact 46. When the armature is attracted by the magnet to throw the weighted arm 26 upwardly and rotate the disk 17 backwardly, the disk and its attachment offer some mechanical resistance to the contact 46 through the medium of the contact 34, and as the disk rotates, the contact 34 slides along the contact 46, and pressure will be exerted upon the contact 46 to one side of the contact 42. As the contact 46 will yield under this pressure, the contacts 42, and 46 will have a sliding action one with relation to the other. This construction also necessitates only the use of a light armature and also insures quick action in winding or resetting of the arm 26 and necessitates a minimum amount of current. When the arm 26 is traveling downwardly the projection 34 first engages the contact 46, after which the contact 46 engages the contact 42.

In order to insure a steady movement to the balance wheel 11, and not interrupt the movement of the balance wheel during the

rising or setting of the arm 26, the arm 21 and the spring 23 are provided. During the falling movement of the arm 26, the pin or projection 25 on the ratchet wheel 20 contacts with the spring 23 and inasmuch as the ratchet wheel is loosely mounted on the collar 15, the ratchet will be rotated slightly with respect to the collar, under the influence of the weighted arm, a sufficient distance to place a stress upon the end 24 of the spring 23 and during the rising movement of the arm 26, the stress of this spring will be exerted upon the shaft 12, after the weight of the arm 26 has been relieved therefrom, to force the shaft 12 forwardly sufficiently to maintain a steady movement of the balance wheel while the arm 26 is being raised. This operation will be repeated as long as the batteries last.

With this improved construction, it will be manifest that all of the parts are exposed and all of the operating or winding mechanism is mounted outside of the clock frame so that easy access may be had thereto. Furthermore, the part 15 is of a single piece construction and is secured to the shaft 12 by the single fastening device 16, so that by releasing the fastening device 30 the parts 15, 20 and 21, may be readily removed from the shaft 12 without dismantling any of the rest of the mechanism.

While the preferred form of construction has been herein shown and described, it is to be understood that various changes may be made in the details of construction, and in the combination and arrangement of the several parts without departing from the spirit of this invention.

40 What is claimed as new is:

1. A self-winding clock embodying an operating shaft, gravity actuated means for actuating the shaft, electrically actuated means for returning the gravity actuated means, said electrically actuated means embodying spaced contacts and an additional contact disposed therebetween, said spaced contacts and said additional contact being movable into and out of engagement with each other, and provisions for causing sparking to take place between only one of the said spaced contacts and the said additional contact.

55 2. A self-winding clock embodying an operating shaft, gravity actuated means for actuating the shaft, electrically actuated means for returning the gravity actuated means, said electrically actuated means embodying spaced contacts and an additional contact disposed therebetween, said spaced contacts and said additional contact being movable into and out of engagement with each other, and provisions for causing sparking to take place between only one of the said spaced contacts and the said additional

contact, one of said contacts operating upon another of the contacts to cause the latter and the remaining contact to have a sliding engagement one with respect to the other.

3. A self-winding clock embodying clock mechanism, said mechanism embodying a shaft, a ratchet wheel loosely connected with the shaft, a yielding connection between the shaft and wheel, said connection embodying an arm, a yielding member connected with and protected by the arm and having a portion spaced from said arm, and a pin adapted to contact with the yielding member to exert stress upon the same in a direction toward the arm, said arm and yielding member, and said pin being connected one with the shaft and the other with the ratchet wheel, a weighted actuating element, a pawl connected with the element and co-operating with the ratchet wheel for actuating the latter, and electro-responsive means for moving the weighted element from an inoperative to an operative position with respect to the ratchet wheel.

4. A self-winding clock, embodying clock mechanism, said mechanism embodying a shaft, a ratchet wheel loosely connected with the shaft, a yielding connection between the shaft and wheel, said connection embodying an arm, a leaf spring connected with and protected by the arm and having a portion spaced from said arm, and a pin adapted to contact with the yielding member to exert stress upon the same in a direction toward the arm, said arm and yielding member, and said pin being connected one with the shaft and the other with the ratchet wheel, a weighted actuating element, a pawl connected with the element and co-operating with the ratchet wheel for actuating the latter, and electro-responsive means for moving the weighted element from an inoperative to an operative position with respect to the ratchet wheel, said weighted element being moved a portion of its distance by its own momentum.

5. A self-winding clock embodying an operating shaft, a pivotally mounted weighted element for actuating the shaft, pawl and ratchet connection between the element and the shaft, and electro-responsive means for returning the said element, said electro-responsive means embodying spaced contacts and an intermediate element into and out of engagement with which both contacts are movable when the circuit of the electro-responsive means is made and broken, the said element operating to cause sparking to take place between said element and only one of the said spaced contacts.

6. A self-winding clock embodying an operating shaft, a pivotally mounted weighted element for actuating the shaft, pawl and ratchet connection between the

element and the shaft, and electro-responsive means for returning the said element, said electro-responsive means embodying spaced contacts and an intermediate element into and out of engagement with which both contacts are movable when the circuit of the electro-responsive means is made and broken, the said element having a sliding engagement with both of said spaced contacts and operating to cause sparking to take place between said element and only one of the said spaced contacts.

7. A self-winding clock embodying an operating shaft, a pivotally mounted weighted operating element, a pawl and ratchet connection between the said shaft and element, electro-responsive means for returning the said element from an inoperative position to an operative position, and a second pivotally mounted weighted element coöperating with the first recited element and operating to initially move the latter in an operative direction.

8. A self-winding clock embodying an operating shaft, a pivotally mounted weighted operating element, a pawl and ratchet connection between the said shaft and element, electro-responsive means for returning the said element from an inoperative position to an operative position, and a second pivotally mounted weighted element coöperating with the first recited element and operating to initially move the latter in an operative direction, said second pivotally mounted element also operating to limit the return movement of the first recited element.

9. A self-winding clock embodying an operating shaft, a pivotally mounted

weighted operating element, a pawl and ratchet connection between the said shaft and element, electro-responsive means for returning the said element from an inoperative to an operative position, a second pivotally mounted weighted element coöperating with the first recited element and operating to initially move the latter in an operative direction, and an adjustable stop for limiting the movement of the second recited element.

10. A self-winding clock embodying clock mechanism, and a supporting frame in which the mechanism is arranged, said mechanism embodying a driving shaft projecting beyond the frame, a pivotally mounted actuating member, a collar detachably secured to the shaft for rotation therewith, a ratchet wheel loosely mounted upon the collar, an element connected with the collar for rotation therewith, a yielding connection between the element and ratchet wheel, said collar, ratchet wheel, element and connections being removable from the shaft as a unit, a pawl connected with the actuating member and coöperating with the ratchet wheel, said actuating member, collar and ratchet mechanism being disposed outside of the frame, and electro-responsive means for controlling the said actuating element.

In testimony whereof I have signed my name to this specification, in the presence of two subscribing witnesses, on this 3rd day of June A. D. 1915.

WILLIAM J. VAN OSDEL.
